UNITED STATES PATENT OFFICE

2,326,506

WALLBOARD FASTENER

Samuel H. Tummins, Houston, Tex.

Application May 9, 1940, Serial No. 334,136

2 Claims. (Cl. 72—118)

This invention relates to a wall board fastener. The invention embodies certain improvements over that type of fastener disclosed in United States Patent No. 2,174,145, issued to applicant herein on September 26, 1939, as well as certain improvements over that type of wall board fastener disclosed in the co-pending application filed in the United States Patent Office on June 16, 1939, by applicant under Serial No. 279,381.

An object of the invention is to provide a fastener of the character described designed for securing wall boards, or panels, to a wall supporting structure and shaped to fit into bevel-lap joints or tongue-and-groove joint between adjacent boards or panels and which, when applied, will be invisible.

Another object of the invention is to provide a fastener of the character described formed of thin, light, strong material which will readily fit into and be concealed in the joint formed between adjacent wall boards, which may be cheaply and easily produced and readily applied and which is very efficient in securing the wall boards in place.

With the above and other objects in view the invention has particular relation to certain novel features of construction and use, examples of which are given in this specification and illustrated in the accompanying drawings, wherein:

Figure 1 shows a fragmentary, elevational view of one form of the fastener employed, in use.

Figure 2 shows an enlarged, fragmentary, horizontal, sectional view taken on the line 2—2 of Figure 1.

Figure 3 shows a perspective view of the fastener.

Figure 4 shows an enlarged fragmentary, horizontal, sectional view taken on the line 2—2 of Figure 1 and illustrating other embodiment.

Figure 5 shows a perspective view of the fastener shown in Figure 4.

Figure 6 shows a fragmentary, elevational view showing a type of fastener shaped to fit into a tongue-and-groove joint.

Figure 7 shows an enlarged, fragmentary, horizontal, sectional view taken on the line 7—7 of Figure 6.

Figure 8 shows a perspective view of the type of fastener illustrated in Figures 6 and 7.

Figure 9 shows an enlarged, fragmentary, horizontal, sectional view taken on the line 7—7 of Figure 6 and illustrating another embodiment of the invention, and

Figure 10 shows a perspective view of the type of fastener illustrated in Figure 9.

Referring now more particularly to the drawings wherein like numerals of reference designate the same parts in each of the figures, the numeral 1 designates the base portion of the fastener which is provided with a nail hole 2 to receive the nail 3. The base is flat so as to fit firmly against the furring strip 4 of the wall supporting structure.

The material of the fastener, at one margin of the base, is retracted forming a clamp 5 which is overturned at an acute angle thus extending diagonally with relation to the base portion. A tang 6, terminating in a sharp point or apex, is thrown outwardly and rearwardly from the material of the fastener as shown in Figures 2 and 3.

The embodiment of the invention shown in Figures 4 and 5 embodies also the flat base portion 1 having the nail hole 2 and provided with the retracted clamp 5a. In this embodiment the clamp has the tangs 6a and 6b thrown out from the material of the clamp rearwardly and forwardly respectively each terminating in a sharp point or apex.

In application the base 1 may be secured to the furring strip 4 by the nail 3 as shown in Figures 1, 2 and 4 with the retracted clamp portion 5, 5a fitting underneath, and closely against the adjacent beveled margin of the wall board or panel 8 with the tang 6 or 6a, as the case may be, penetrating into the said adjacent margin. It may be here noted that the tangs 6, 6a, 6b extend out approximately parallel with the base portion 1. The next panel or wall board as 9 may then be brought into place and, with the form or fastener shown in Figures 1, 2 and 3 may be readily adjusted until it is brought into exact alignment with the panel 8, previously secured in place, and when in the proper alignment this panel 9 may then be secured, at its outer free margin, to the furring strips 4 by additional fasteners indicated by the numeral 1a in Figure 1. It is to be further noted if the type of fastener shown in Figure 5 is employed as each additional panel is brought into place it must be exactly aligned with the last preceding panel of the tier and as it is forced to final home position the tang 6b will penetrate into it in the manner illustrated in Figure 4.

It is accordingly to be noted that the fastener shown in Figure 3 will hold one margin of the adjacent panel to the supporting frame work by the tang 6 and also will hold the adjacent margin of the adjoining panel closely against the supporting frame work by the clamp 5. When the form shown in Figure 5 is used the adjacent margins of adjoining panels will be firmly held

against the supporting structure by the clamp 5a and the tangs 6a, 6b.

In the embodiment illustrated in Figures 6 to 10 inclusive, types of fasteners are shown specially adapted for use with wall boards or panels having tongue-and-groove joints between adjacent boards. In these forms the base is indicated by the numeral 1b adapted to be secured to the wall supporting structure in the same manner as shown in Figures 1 to 5 inclusive. The base 1b has a retracted clamp portion 5b as more clearly illustrated in Figure 8 or 5c as clearly shown in Figure 10, the only difference being that the clamp 5b diverges slightly from the base 1b and the clamp portion 5c lies approximately parallel with the base portion 1b. This is also illustrated in Figures 7 and 9. The free margins of the clamp portions 5b, 5c are overturned approximately at right angles to the base portion forming an abutting flange 10 which abuts the free end of the tongue 8b of the wall board or panel 8a. In both forms shown in Figures 8 and 10 the clamp portion overlies and clamps the inner bead 9b of the wall board or panel 9a as clearly shown in Figures 7 and 9.

In use the base 1b may be secured to the furring strip 4 with its clamp portion embracing the bead 9b and with its flange 10 abutting the outer end of the tongue and with its tang 6c penetrating into the adjacent margin of the board or panel 8a as illustrated in Figure 7. When the adjacent wall board 9a is brought into place it can be adjusted into exact alignment with the adjoining wall board 8a and when moved into final home position the clamp 5b will securely clamp against and embed itself into the corresponding bead 9b of the board or panel 9a. Its free margin may then be secured to the furring strips by the fasteners 1c.

When the former fastener shown in Figures 9 and 10 is employed the panel 9a should be exactly aligned with the panel 8a and when brought into its final home position its tang 6d will penetrate into the material of the panel 9a and its clamp portion 5c will fit over and clamp the bead 9b of said panel 9a.

In all of the forms the fasteners will securely hold adjacent margins of adjoining wall boards or panels to the corresponding furring strips and will be completely concealed from view.

The drawings and description are illustrative merely while the broad principle of the invention will be defined by the appended claims.

15. What I claim is:

1. A wall board fastener comprising a substantially flat base, a clamp portion retracted from and formed integrally with the base and adapted to clamp a portion of the adjacent margin of a wall board overlying the base and tangs thrown out from the material of the retracted clamp portion and projecting in opposite directions from the clamp portion and adapted to penetrate into adjacent margins of said overlying wall board and of another wall board.

2. A wall board fastener comprising a substantially flat base, a retracted clamp portion extended from and formed integrally with the base and terminating in an upturned end portion lying in a plane approximately perpendicular to the plane of the base and tangs thrown out from the material of said upturned portion and projecting in opposite directions from the upturned end portion, each tang lying in a plane approximately parallel with the plane of the base.

SAMUEL H. TUMMINS.
